DISPLAY SIGN

Robert B. Fleming, Kenmore, N. Y., assignor to
Edward J. Brunner, Buffalo, N. Y.

Application August 31, 1938, Serial No. 227,796

2 Claims. (Cl. 40—76)

This invention relates generally to an advertising display but more particularly to a changeable sign designed for advertising and like purposes.

It has for one of its objects to provide a sign of this character which is so designed and constructed as to create a novel, distinctive and automatic changing position or appearance to thereby attract attention, and which produces a plurality of different sign displays at predetermined intervals from one composite unit or assembly.

Another object of the invention is to provide a changeable sign having a plurality of juxtaposed, independently movable sign panels bearing sign data on a plurality of its faces to collectively create a composite sign when exposed for display, and means engageable with the sign panels for successively moving or turning them at predetermined intervals to one display position or another.

A further object is the provision of a sign of this character which is simple, compact and inexpensive in construction and which is reliable and efficient in operation. Other features of the invention reside in the construction and arrangement of parts hereinafter described and particularly pointed out in the appended claims.

In the accompanying drawing:

Figure 1 is a front elevation of my improved sign showing the sign elements or panels in one position to create a given sign display. Figure 2 is a similar view but showing the same sign elements in a different position to create another sign display. Figure 3 is an enlarged rear view of the sign with the rear cover plate removed. Figure 4 is an enlarged transverse vertical section taken substantially in the plane of line 4—4, Figure 3. Figure 5 is a fragmentary perspective view of a pair of adjoining sign panels and the means associated therewith for effecting the movement of such panels to different sign-displaying positions. Figure 6 is a fragmentary perspective view of a modified construction for individually retaining each sign-panel in a given position as well as for cushioning its movement to a given display position. Figure 7 is a fragmentary perspective view showing a modified construction for retaining the sign-panels in properly aligned display position.

Similar characters of reference indicate corresponding parts throughout the several views.

Referring now to the drawing, 10 indicates the casing which may be of any appropriate shape and construction and in which the various working parts of the sign are mounted and housed,

its front side being provided with an opening 11 for the display of the sign.

Extending across the open front side of the casing are a plurality of individually and independently movable sign elements or panels 12 having sign-data on a plurality of faces thereof and disposed side by side in uniform or symmetrical fashion to collectively produce a unitary or composite sign display when one side or another of the sign-panels are exposed to view, so as to produce at one time, for example, the display pictured in Figure 1 and at another time the display seen in Figure 2. These sign-panels are, by preference, disposed vertically in substantially contiguous parallel relation in a common plane in the front portion of the casing and each is individually mounted to swivel or revolve about upright pivot-pins 13 projecting centrally from the upper and lower ends thereof and detachably seated in companion bearing-sockets or openings 14, 15 formed in bearing plates 14, 15 applied to the casing along the upper and lower edges of its opening 11. The panels disclosed herein are in the form of slats and provide two faces for bearing sign-data, and in display position are just spaced at their opposing edges sufficiently to provide proper edge-clearance for relative turning movement.

At its lower end, and concealed from view, each panel 12 is provided with a plurality of radial vanes or trip elements 16 which may be secured to or form an integral part of the companion pivot-pin 13 and each of which in a predetermined position, is adapted to project over and in the operating path of an actuating member 17 common to the several panels and having one or more lugs or tappets 18 thereon disposed for engagement with companion panel-vanes in its path, whereby the panels from end to end of the casing are successively turned or reversed about their pivots a distance of 180 degrees to effect the disappearance of one sign display, say the one shown in Figure 1, and bring into view the other sign display shown in Figure 2, the cycle of operations being continuous to alternately display the respective signs. By preference, each sign-panel has four equidistant radial vanes 16 thereon and the actuating member is in the form of an endless band of belt connected at its ends to companion pulleys 19 applied to shafts 20 mounted in the lower portion of the casing 10, as shown in Figures 3 and 4. This band is adapted to be driven continuously at a comparatively slow speed and to this end one of

these pulleys includes a second pulley 21 connected by a belt 22 to a suitable driving motor 23, which may be of the electric or any other well known type. The actuating member or belt

- 5 17 is preferably provided with two adjoining tappets 18, so that the leading tappet will first encounter those trip-vanes 16 of the several panels in its direct path to turn each panel a quarter turn, following which the trailing tappet will 10 encounter the next presented trip vane of each panel and turn it another quarter turn, to thereby successively turn or flip the several panels a half revolution during the travel of the tappets past the respective panels and present the opposite faces thereof to view to alternately change the sign display. While four trip elements and two companion tappets are desirable to produce a smooth and quiet turning action of the sign panels, it is to be understood that the panels 15 may be flipped by providing but two diametrically-disposed trip elements and one tappet, in which case each panel is turned a half revolution at each tappet-contact with a companion trip element.

25 For the purpose of yieldingly restraining the turning of the sign-panels 12 and maintaining them in uniform or properly aligned display position, I provide a swinging bail 24, which is common to and bears against the rear sides of the several panels, as shown in Figures 2 and 3, and which is hinged at its ends at 25 to the sides of the casing 10, a light spring 26 being applied thereto for urging it against such panels. If desired, however, each panel may be provided 30 with a cam-like member 27 with which a flat spring 28 bears, as shown in Figure 6, whereby the several panels are individually governed in their turning movements and maintained in proper alignment in sign-displaying position.

35 40 In Figure 7 I have shown a further modified arrangement for retaining the sign-panels in display position, wherein one of the trip-vanes 16 is provided at its lower edge with a teat or projection 29 adapted to register and drop by 45 gravity into one or the other of a pair of shallow radial grooves 30 formed in the adjoining face of the bearing plate 15 when the companion sign-panel is presented in one or the other of 50 its display positions. During turning or flipping

of the sign-panels, their teats 29 ride freely out of the registering grooves.

I claim as my invention:

1. A changeable sign of the character described, comprising a casing having a sign display-opening in its front side, bearing plates applied to the upper and lower edges of said display-opening and having bearing sockets therein, a plurality of individually movable sign-panels of substantially slat-like form disposed 10 in edgewise relation in the plane of said casing-opening to provide a composite display and each bearing sign data on its opposite faces and pivot pins projecting centrally from the upper and lower ends thereof engageable with companion 15 sockets in said bearing plates, trip elements extending radially from one of the pivot pins of each sign-panel, shafts journaled in the front portion of said casing at opposite ends thereof and below the sign-panels and at right angles to 20 the pivot pins thereof, pulleys applied to said shafts, an endless belt engaging said pulleys and having tappet means applied to the outer face thereof for operative engagement with said trip elements for successively and intermittently imparting a swiveling movement to the sign-panels 25 to expose one side or the other to display position, a source of power connected to one of said pulley-shafts, and resilient retaining means operatively associated with the sign-panels for releasably retaining them in their aligned display 30 position.

2. A changeable sign of the character described, comprising a plurality of individually movable sign-panels disposed in substantially 35 edgewise relation to provide a composite display and each bearing sign data on a plurality of its faces, means for mounting said sign-panels for individual swiveling movement to expose one 40 side or another of their sign-data-bearing faces, an actuating means for moving said sign-panels at predetermined times to different display positions, complementary means applied to said sign-panels and to said actuating means for governing the successive swiveling movements of the 45 sign-panels to such positions, and a yieldably-suspended bail engageable with the sign-panels for releasably retaining them in uniform display position.

ROBERT B. FLEMING. 50
